(57) **CLAIM**

The ornamental design for a device for use with a belt for coupling a gun holster, as shown.

DESCRIPTION

FIG. 1 is a front perspective view of a device for use with a belt for coupling a gun holster showing my new design;

FIG. 2 is a rear perspective view thereof;

FIG. 3 is a rear elevation view thereof;

FIG. 4 is a right side elevation view thereof;

FIG. 5 is a bottom plan view thereof;

FIG. 6 is a front elevation view thereof;

FIG. 7 is a left side elevation view thereof;

FIG. 8 is a top plan view thereof; and,

FIG. 9 is a front elevation view of an internal part of FIG. 6.
